TEXTILE FINISHING MACHINE

Wallace Taylor, Pawtucket, R. I., assignor to The Textile-Finishing Machinery Company, a corporation of Rhode Island

Application March 4, 1935, Serial No. 9,198

3 Claims. (Cl. 91—32)

This invention relates to a textile finishing machine, more particularly for starching a web of textile fabric; and has for one of its objects the provision of a single machine which will be capable of use for the usual process of starching or alternatively for use for starching from one side only, commonly called back filling.

Another object of the invention is the provision of fabric guides upon opposite sides of the machine, one of which set of guides may be used where ordinary starching is employed, and the other set of guides on the other side of the machine used where back filling is employed, the arrangement being such that each set of guides is entirely independent and each so located as not to interfere with the other when in use.

Another object of the invention is the provision of different driving means for the rolls for handling the web material which utilize some parts common to both drives to combine the structure of a single machine for the two purposes.

Another object of the invention is the utilization of the parts of one machine for two different purposes which were ordinarily duplicated in separate machines.

Another object of the invention is the simplification of the machine by causing the agitator and the oscillating doctor blade to be operated from a single end of the machine by a common means.

Another object of the invention is the saving of floor space in a mill by the utilization of one unit where two units were formerly employed occupying double the floor space.

With these and other objects in view, the invention consists of certain novel features of construction, as will be more fully described, and particularly pointed out in the appended claims.

In the accompanying drawings:

Fig. 1 is an elevation of my machine with the roll in raised position for use of the machine for back filling;

Fig. 2 is a front elevation thereof;

Fig. 3 is a sectional view illustrating the operating parts of the machine and the guiding of the work therethrough for back filling;

Fig. 4 is a sectional view similar to Figure 3, illustrating the upper guide roll for the work as lowered into operating position and the fabric as passing through the machine for starching from both sides;

Fig. 5 is an elevation of a part of the machine, illustrating the drive for the arrangement shown in Figure 4 and omitting many of the parts shown in Figure 1 for the sake of clearness of this drive;

Fig. 6 is a fragmental view looking at the ma-

chine from the same position as Figure 1 and bringing out in greater detail the mounting and operation of the oscillating doctor blade.

Heretofore in certain cloth finishing operations a starch mangle has been used for the full starching of the fabric, this machine being a single unit by itself. When back filling instead of full starching is desired for the fabric a separate machine for this purpose sometimes called a "Tommy Dodd" mangle has been used, each separate machine always performing its own function and never capable of being utilized by reason of its different construction for the function of the other; and in order that floor space may be saved and parts used for both operations, I have provided a machine in which both of these operations may be accomplished by the simple setting of the machine to adapt it for either purpose; and the following is a more detailed description of the present embodiment of this invention, illustrating the preferred means by which these advantageous results may be accomplished:

With reference to the drawings, I have provided standards 10 and 11 suitably connected together as at 12 and each of which standards is of a generally similar construction. As shown in Figure 1 each standard consists of a base portion 13 and an upright portion 14, which upright is provided with an opening 15 the edges 16 of which form a slideway at its opposite sides.

At the base of the standards 10 and 11 a bracket 17 is suitably mounted which supports the end frame 18 of a tank 19 which contains the treating liquor 20.

Bearings 21 are fixed in the standard 10 and 11 which support a shaft 22 extending from the bearing in standard 10 to and through the bearing in the other standard 11 and upon which between the standards there is mounted a work-immersing roll 23 while the shaft beyond the last said bearing is driven, as later explained. The level of the treating liquor is kept just above the axis of the treating roll 23, thus about one-half of the roll is immersed in the treating liquor and the other half is out of the treating liquor.

At a point above the liquor tank, bearings 24 are slidably supported by means of cross-head members 25 in the slideways 16. These bearings support a shaft 26 upon which there is splined a guide roll 26a. This shaft 26 also extends beyond the standard 10 to be suitably driven, as will hereinafter be explained.

Above the bearings 24, bearings 27 are slidably mounted in the standards similarly to bearings 24, which bearings rotatably support a shaft 28

upon which there is mounted a roll 29. The cross-head member 25 is provided with openings in lugs 30, while a cross-head member 31 supports the bearing 27 and is provided with similar 5 openings. These openings are vertically aligned to slidably receive rods 32 which are provided with abutment means, in the form of a nut 33 and check nut 34, at either end providing a length between the abutments greater than the distance 10 between the centers of the rolls 26a and 29 and providing a structure such that when the bearing 27 is lifted, it will after an initial movement, in turn lift the bearings 24 through the rods 32.

Above the bearing 27 there is a sliding cross-head 35 having similar openings and which is connected to the member 31 by rods 36 in the same manner that the member 31 is connected to the member 25 by the rod 32. This member 35 may rest upon the upper edge of the bearing 27 and has attached thereto a threaded shaft 37 which is provided with a nut 38, supported at the upper end of the machine upon a pivoted lever 39 pivoted as at 40. The threaded shaft 37 is provided with a hand wheel 41 at its upper end so that upon turning the same the member 35 will be drawn upwardly and will in turn draw up the member 31 and the member 30 to lift the rolls vertically of the machine.

When the rolls are lowered to the position 30 shown in Figure 4, pressure is applied on the upper bearings 27 and in turn upon the bearings 24 by a thrust being transmitted through the threaded shaft 37. A lever 39 is pivoted at 40 and pulled downwardly, through the rod 43 which 35 connects the free end of lever 39 and the lever 44 which is pivoted as at 45 and weighted as at 46 at its end 47. These weights 46 can be adjusted to apply the desired amount of pressure upon the rolls. This arrangement, of course, is 40 provided on each of the standards, and the weights will in ordinary use be alike on both sides of the machine.

Assuming this machine is to be used for back filling, the web of work or material designated 45 50 will be led from suitable source of supply downwardly about the guide roll 51, thence beneath the tank of treating liquor about the guide roll 52 upwardly and about the guide roll 53 and thence through a Mycock expander 54 of usual 50 and known construction supported from the base of the standard by a post 55, thence across the scrimp rail 56 to contact with the roll or cylinder 23 at a point above the liquid level 57. The work is held tight about the cylinder as it is passed 55 through the starch or treating solution so that the starch enters the web only from one side which is generally termed back filling. The work then is guided about the roller 58 suitably supported in bearings 59 on both standard 10 and 11 and 60 then upwardly or to some suitable location to be again packaged or otherwise treated.

The solution is agitated by a suitable agitator or drum with fins 59 thereon located adjacent the bottom of the tank and driven as will be explained. 65 A bearing 60 is mounted upon standard 10 which rotatably supports the power shaft 61 through which power is derived for operating the machine. Upon this shaft there is provided a pulley 62 which drives the expandable pulley 63 through 70 a suitable belt 64. This pulley 63 is keyed to shaft 65 rotatably mounted in the bearings 66 on the standard 10 and a bearing 67 supported by the legs 68. Upon this shaft there is secured a gear 69 which meshes with a gear 70 slidably 75 supported in the slot 71 in a bracket 72, which

gear 70 also meshes with a gear 73 on the end of shaft 22 for rotating the roll 23 which is partially immersed in the treating liquor bath.

Upon the shaft 22, there is also provided a sprocket gear 74 over which a sprocket chain 75 5 is trained also engaging sprocket gear 76 on the agitator shaft and sprocket gears 77 and 78 for driving the doctor blades to be described. A roll 107 mounted upon an arm 108 is pivoted on the frame 10 as at 109 and is moved to engage the 10 sprocket chain 75 to take up any slack which may occur in the same, it being apparent that the doctor blade and the agitator are driven from a common means and at one end of the machine, thereby simplifying the construction of operation 15 of these parts materially.

There are two doctor blades designated 80 and 81. Both of these are reciprocated axially of the roll 23. Each is mounted in the upright standards 10 and 11. There is provided a carriage 82 20 vertically adjustable on the gibbs 83. On this carriage 82 there is a slide 84 which is horizontally adjustable on the track 85. Each of the doctor blades is mounted in a holder 86 which is provided with pins 87 at either end, which pins 25 lodge in the U-shaped bearing 88 fixed on the slide 84, while at a point half-way between the ends or centrally of the holder 86, there is provided an eye 89 to which an arm 90 is connected. This arm at its other end is connected to the 30 crank pin 91 secured to the worm wheel 92 which meshes with the worm 93 secured to shaft 94 driven by a sprocket wheel 77 or 78. The position of the doctor blade is adjusted vertically through the threaded shaft 95 extending through 35 the threaded boss 96, while it is adjusted horizontally by the threaded shaft 97 operated by a hand wheel 98 through the threaded bearing 99 on the carriage 82.

If it be desired that the machine be used for 40 the starching operation from both sides of the web, a different drive is had. In this case, the work now designated 101 is led over the guide pulley 102 into the bath then in contact with the roll 23 for about a quarter of its surface, then 45 about the roll 26a and roll 29 now both lowered so that roll 26a is in pressing relation with roll 23, as shown in Figure 4, and thence outwardly as at 103, to some suitable packaging means. When the machine is put to this use, the gear 70 which 50 heretofore drove the gear 73 and the roll 23, is now slid out of mesh with gear 73 by moving its bearing along the slotted portion of the bracket 71, which at the same time moves this gear out of mesh with gear 69. When the roll 26a is 55 moved downwardly, a gear 104 on the end of shaft 26 moves into mesh with gear 105 keyed to the power shaft 61 so that now the power shaft drives the smaller roller 26a which in turn frictionally drives the rollers 23 and 29 below and above it 60 through contact with the cloth, and the lower roll 23 by reason of being driven will, of course, continue to drive the agitator and the doctor blade, although as pressure is applied in this use of the machine to the rolls, any excess starch is 65 freed from the work as it interweaves or passes between the rolls so as to drain back into the bath.

It will, of course, be apparent a single unit occupying the space of but a single machine is now 70 provided which can be readily arranged through very convenient means to operate either as a direct starching machine or as a back filling machine by a simple rearrangement of its operating parts.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a fabric treating machine, a bath of treating liquor, a work conducting roll partially immersed in said bath, a doctor blade adjacent the upper portion of said work conducting roll, means to oscillate said blade, means to agitate the treating liquor, and means for driving said oscillating and agitating means at the same end of the machine.

2. In a fabric treating machine, a bath of treating liquor, a work conducting roll partially immersed in said bath, a doctor blade adjacent the upper portion of said work conducting roll, means to oscillate said blade, means to agitate the treating liquor, and a common means for driving said oscillating and agitating means.

3. In a fabric treating machine, a bath of treating liquor, a work conducting roll partially immersed in said bath, a doctor blade adjacent the upper portion of said work conducting roll, means to oscillate said blade, means to agitate the treating liquor, and a common means for driving said oscillating and agitating means from said conducting roll.
